UNITED STATES PATENT OFFICE.

GUIDO CHIARCOSSI, OF POWELL RIVER, BRITISH COLUMBIA, CANADA.

HOLDER FOR MILK BOTTLES.

Application filed September 10, 1924. Serial No. 736,884.

To all whom it may concern:

Be it known that I, GUIDO CHIARCOSSI, a subject of the King of Italy, and a resident of Powell River, in the Province of British Columbia, Canada, have invented certain new and useful Improvements in Holders for Milk Bottles, of which the following is a specification.

My invention relates to improvements in holders for milk bottles, the objects of which are to provide means whereby a bottle of milk on delivery is placed into the holder and is automatically locked therein and the bottle top covered to prevent contamination. A further object is to provide means whereby the removal of the bottle is rendered possible to any person within the dwelling to which the holder is attached.

The invention consists essentially of a shallow container mounted upon a vertical panel and is adapted to be secured outside a suitable wall adjacent a door, a cover for holding the bottle in the container and means extending through the wall for releasing the bottle holding means, as will be more fully described in the following specification in which:—

Fig. 1 is a sectional view of my invention taken through the container with the cover raised to receive the milk bottle.

Fig. 2 is a sectional view showing the bottle held in place by the cover.

Fig. 3 is a rear sectional view taken on the line 3—3 of Figure 1.

In the drawings like characters of reference indicate corresponding parts in each figure.

The numeral 1 indicates a hollow vertical panel having a rear wall 2 and a front wall 3, which latter is provided with vertical slot 4 along which the cover is movable, and 5 is an aperture through which the trigger 18 extends.

The numeral 6 indicates a circular container of a diameter substantially equal to the largest sized bottle which is liable to be deposited therein. The numeral 7 indicates a cover which is adapted to fit closely upon the top of a milk bottle and is preferably lined on its underside with a cork disk 8 which serves to cushion the impact of the cover when dropping upon the bottle top and also to exclude dust and flies therefrom. The cover 7 is carried upon an arm 9 extending from a sleeve 10 having sliding movement upon a vertical rod 11 suitably journalled

between the front and rear walls 2 and 3 of the panel 1.

The numeral 12 indicates a spring pressed bolt horizontally movable in a casing 13 mounted upon the rear wall 2, the inner end 14 of the bolt 12 being splayed to engage any one of the teeth 15 of the sleeve 10 when the cover is dropped into contact with the bottle. At the outer end of the bolt 12 a cord 16 is provided which is adapted to be led through the wall onto which the bottle holder is secured, for the purpose of releasing the bolt from engagement with the sleeve and to permit the cover 7 to be raised for the removal of the bottle.

The numeral 17 indicates a rod vertically movable within the panel 1 which is bent to a right angle through the aperture 5 to form a trigger 18 which is depressed by the weight of the bottle. The upper end of the rod is pivotally connected to a bell crank 19 which is mounted upon a pin 20 and is adapted to engage the lower extremity of the sleeve 10 to hold it and the cover 7 in raised position.

Having thus described the several parts of my invention I will now briefly explain its use.

The bottle holder is preferably secured to the outside of an outer wall in close proximity to a door and the cord 16 carried through to the inner side of the wall, so that the bottle and the cord may be conveniently reached from the door opening. The bottle holder is set with the cover raised as shown in Figure 1, and when a bottle is deposited within the container 6 its weight depresses the trigger 18 imparting a downward movement to the rod 17, releasing the bell crank 19 from engagement with the sleeve 10, thereby permitting the cover 7 to fall onto the bottle top, when the bolt 12 engages the sleeve 10 to prevent the cover from being raised.

To remove the bottle it suffices to pull the cord 16 and raise the bottle and the cover 7 until the bell crank 19 engages the lower extremity of the sleeve 10 and then withdraw the bottle from the device, which leaves it set for the reception of another bottle.

What I claim as my invention is:

1. A bottle holder comprising a base member shaped to provide a pocket for receiving the bottom of a bottle, a hollow casing carried by the base member and extending perpendicular thereto, a vertical guide

rod mounted within and extending longitudinally of said casing, a carriage slideable vertically on said rod and carrying a cap member adapted to fit over the upper end of the bottle, a spring pressed latch operating in an opening formed in a wall of the casing and adapted to engage teeth formed on the carriage when the latter is in a position opposite said latch member, a trigger engageable with the carriage to support the same in elevated position with respect to said latch member, a depressible element positioned in the base member and adapted to be depressed by the weight of a bottle placed thereon and a connection between the depressible member and the trigger operating to release the carriage for gravitational movement when a bottle is placed in the base member, said latch serving to automatically engage the teeth of the carriage to secure the cap member upon the top of the bottle.

2. A milk bottle holder comprising a base member, a guide rod supported to extend vertically with respect to said base mem-

ber, a carriage slideable on said rod and equipped with a cap member adapted to fit over the upper end of a bottle having its lower end engaged in the base member, a trigger in the form of a pivotally mounted bell-crank having one arm disposed to reach beneath the carriage to support the latter when in elevated position, a vertically movable rod having its upper end connected to the remaining end of the bell-crank and its lower end bent at right angles and disposed in the base member so as to be depressed by the weight of a bottle, and a spring encircling said rod and confined between an upper abutment on the rod and a lower stationary abutment, said spring serving to normally hold the trigger in carriage engaging position and with the lower end of the rod resiliently held above the bottom of the base member.

Dated at Powell River, B. C., this 22nd day of August, 1924.

GUIDO CHIARCOSSI.
